ATTORNEY

UNITED STATES PATENT OFFICE

LOESER KALINA, OF BROOKLYN, NEW YORK

GARMENT HANGER

Application filed November 25, 1930. Serial No. 498,001.

The present invention relates to new and useful improvements in garment hangers, and more particularly it pertains to a garment hanger in which a certain insect destroying medium is associated therewith.

It is one of the objects of the present invention to provide a new and novel garment hanger of the aforementioned type which will be simple in construction and cheap to manufacture.

It is a further object of the invention so to construct a garment hanger that when garments are carried thereby, they will be subjected to the action of an insect destroying medium during the time which they are carried by the garment hanger.

It is a still further object of the invention, so to construct a garment hanger that the insect destroying medium may be applied thereto or removed therefrom readily at will.

Other objects of the invention relate to certain novel and improved constructions, arrangements and combinations of parts hereinafter described and particularly pointed out in the claims, the advantages of which will be readily understood and appreciated by those skilled in the art.

The invention will be clearly understood from the accompanying drawing illustrating the invention in its preferred forms and the following detailed description of the constructions therein shown.

In the drawing,

Figure 1 is a view in side elevation partly broken away of a coat hanger constructed in accordance with one form of the present invention,

Figure 2 is a top plan view of that form of the invention illustrated in Figure 1,

Figure 3 is a plan view of a blank from which the garment supporting portion of the hanger illustrated in Figures 1 and 2 is formed,

Figure 4 is a transverse sectional view taken on the line 4-4 of Figure 1.

Referring to the drawing, and particularly to Figures 1 to 3 inclusive thereof, it will be noted that the garment hanger comprises two members 10 and 11. The member 10 is formed from relatively thin and light sheet metal,

and the blank from which this member is formed is illustrated in Figure 3 and consists of a main body portion 12, having side flanges 13 which are adapted to be bent into a plane at substantially right angles to the main body portion 12. The main body portion 12 is provided with end extensions 14 and a projecting resilient finger 15 upon each end thereof. The side flanges 13 terminate in curved ends 16, and throughout their length are provided at desired intervals with tongue like members 17 which are adapted to be bent inwardly of the side flanges 13 for a purpose to be hereinafter described.

In forming the member 10, the blank is bent along the line indicated at 18 to form the side flanges 13 heretofore mentioned after which the end extensions 14 are bent downwardly and the resilient fingers 15 bent inwardly as best illustrated in Figure 1.

The member 11 consists of a wire mesh fabric of relatively large mesh and it comprises a rectangular blank bent into curved form in cross section, and of such dimensions as to be readily received within, or between the flanges 13 of the member 10 as best illustrated in Figure 4. Referring to Figure 4 it will be noted that when the member 11 is bent to shape, it is only necessary to insert the edges of the sides of the member 11 into position between the flanges 13 of the member 10, whereupon the tongues 17 heretofore mentioned will engage the members of the mesh of the member 11 and return the same in position. When the member 11 is placed in position, the end extensions 14 form closures for the ends of the member 11, and the resilient fingers 15 engage the ends of the member 11 as illustrated at 20 in Figure 1. By this means the member 11 will be retained in position in conformity to the member 10 with its ends closed as described.

The member 10 may be provided with a plurality of preforations such as 21 on its top wall, and it may also be provided with a relatively large opening 22 closed by a closure plate 23 which may be pivotally mounted as at 24 upon the supporting hook 25.

The construction just described provides a hollow garment hanger which is formed of

two pieces which may be readily attached or detached with respect to each other which hollow garment supporter is adapted to carry a destroying medium for moths and other insects. In the present illustration of the invention, this insect destroying medium is preferably in the form of moth balls such as 26, and they may be inserted to position within the garment hanger merely by swinging the closure plate 23 of the opening 22 to one side and dropping the moth balls through the opening 22 after which the closure plate 23 is moved to closed position in which it is illustrated in Figure 2.

From the foregoing it will be apparent that the present invention provides a new and novel form of garment hangers, at the same time providing new and novel means whereby insect destroying medium such as moth balls may be associated with the garment hanger in a cheap and economical manner which at the same time permits of ready renewal of the insect destroying medium as required.

While the invention has been herein illustrated in its preferred forms, it is to be understood that the invention is not to be limited to the specific constructions herein illustrated, and that it may be carried out in other forms without departing from the spirit thereof.

Having thus described the invention, what is claimed as new and what it is desired to secure by United States Letters Patent, is:

1. A garment hanger comprising a main body portion channel-shaped in cross-sectional form, a foraminous insecticide carrier, and a plurality of projections extending inwardly of the side walls of said main body portion and adapted for engagement with certain of the openings of the foraminous member for securing the insecticide carrier to the main body portion.

2. A garment hanger comprising a main body portion channel-shaped in cross-sectional form, a foraminous insecticide carrier, and a plurality of projections extending inwardly of the side walls of said main body portion and adapted for engagement with certain of the openings of the foraminous member for securing the insecticide carrier to the main body portion, and extensions on the ends of the main body portion also forming means for securing said members together.

3. A garment hanger comprising a main body portion of sheet metal, said body portion being channel-shaped in cross-sectional form, and an insecticide carrying member of U-shape in cross-sectional form, and formed of wire mesh, means for securing said members together to form the main body portion of a coat hanger, and means integral with said sheet metal member for closing the ends of said insecticide carrying member.

4. A garment hanger comprising a main body portion of sheet metal, said body portion being channel-shaped in cross-sectional

form, and an insecticide carrying member of U-shape in cross-sectional form, and formed of wire mesh, means for securing said members together to form the main body portion of a coat hanger, and means integral with said sheet metal member for closing the ends of said insecticide carrying member, said last mentioned means comprising tongue extensions on the ends of said sheet metal member.

5. A garment hanger comprising a main body portion of sheet metal, said body portion being channel-shaped in cross-sectional form, and an insecticide carrying member of U-shape in cross-sectional form, and formed of wire mesh, means for securing said members together to form the main body portion of a coat hanger, and means integral with said sheet metal member for closing the ends of said insecticide carrying member, and hook extensions projecting from said tongue extensions for fastening engagement with said insecticide carrying member.

6. A garment hanger composed of upper and lower elongated members, said lower member being formed of wire mesh and of U-shaped formation in cross-section and said upper member having depending edges overlapping outwardly the edges of the lower member and fixedly attached thereto.

Signed at Brooklyn, in the county of Kings and State of New York, this 20th day of November, A. D. 1930.
